UNITED STATES PATENT OFFICE

2,558,595

EXPANDING BRAKE OPERATING
MECHANISM

Ivan Waller, Duffield, England, assignor to Rolls-Royce Limited, Derby, England, a British company

Application September 23, 1947, Serial No. 775,675

5 Claims. (Cl. 188—78)

1

This invention relates to brakes such as are used on vehicles, comprising a brake-drum with a pair of shoes either pivotally mounted or floating inside the drum, with means for pressing them outwards against the inner surface of the drum to exert the braking effect, and has for its object to provide an improved construction which is simple and more satisfactory in operation.

According to this invention there is provided in a brake having internal expanding shoes, an expander mechanism comprising two bell-crank levers pivotally located on a carrier-bracket and engaging respectively the free ends of the two brake-shoes each by one arm, and each having its other arm operatively connected to the brake-operating rod.

According to a feature of this invention the second arm of one of the bell-crank levers is directly coupled to the operating rod, and engages the second arm of the other lever to rock it in the brake-applying direction.

Preferably the engaging surfaces of the two said arms of the levers are shaped to give a relative rolling action between them, with the minimum amount of sliding.

According to another feature of the invention, the carrier-bracket is trough-like and of U-section and the bell-crank levers are accommodated between the limbs of the bracket and respectively pivotally engaged with opposite ends of the bracket by trunnions on the levers engaging in recesses in the end surfaces of the limbs of the bracket. The form of these trunnions and recess is such as to provide considerably lower frictional losses than would be possible with conventional pivot pins large enough to carry the operating loads.

One embodiment of this invention will now be described by way of example, reference being made to the accompanying drawings, in which:

Figure 1 is an elevation of a brake mechanism having an expander mechanism according to this invention,

Figure 2 is a section on a reduced scale on the line 2—2 of Figure 1, and

Figure 3 is an exploded view on a reduced scale of the bell-crank levers and their carrier-bracket showing details of construction.

The brake is of usual construction in so far as it comprises a brake-drum 10, a fixed carrier plate 11 mounted within the drum 10, two brake shoes 12, 13 pivotally mounted on the carrier plate 11 each at one end, an expander mechanism to operate on the free ends of the shoes 12, 13 to

2

force them outwards into contact with the drum and springs 14 for withdrawing the shoes from contact with the drum.

The expander mechanism according to this embodiment of the invention comprises a trough-shaped carrier-bracket 15 of U-section which is secured to, or alternatively which floats upon, the fixed carrier plate 11 adjacent the free ends of the shoes 12, 13. Within the trough 15 between the two limbs 16 thereof there are mounted a pair of bell-crank levers 17a, 17b each having a long arm 18a or 18b which extends lengthwise along the bracket and a short arm 19a or 19b, the short arms engaging respectively with the shoes 12, 13. Each bell-crank lever is formed with lateral extensions 20 of a trunnion-like formation to constitute its pivotal mounting and these trunnions 20 lie in suitably rounded recesses 21 in the end surfaces of the limbs 16 of the carrier-bracket 15. As will be seen from the drawing the lateral extensions 20 are of wedge form having their narrower ends rounded to provide an arcuate edge of small radius of curvature. The radius of curvature of the rounded edge is substantially less than that which would be required for a pivot pin to support the operating loads. The form of the trunnions 20 and recesses 21 provide considerably lower frictional losses than is possible with conventional pivot pins large enough to carry the operating loads, being in the nature of an arcuate knife edge bearing.

After the expander mechanism is assembled the levers 17a, 17b are retained in place by the action of the pull-off spring 14 acting between the shoes 12, 13 and by the brake-operating forces, but in order to retain them in position during assembly or dismantling of the brake, small projections or pins 22 are provided extending outwards, one from each trunnion 20, to be engaged by spring-plates 23 located on the outer side of the limbs 16 of the bracket 15. These spring plates 23 are secured to the bracket 15 and yield sufficiently at their ends to permit the insertion of the levers 17a, 17b into place so that the pins engage in holes in the spring-plate 23 and are retained thereby.

The long arms 18a, 18b which lie lengthwise in the carrier-bracket 15, overlap one another and their abutting surfaces 24a, 24b are rounded so that when subjected to angular movement, a rolling action is obtained between them with as little relative sliding movement as possible.

The brake-operating rod 25 extends through an opening in the brake cover plate 26 and this opening is sealed against the ingress of dirt and

the like by a legging 27, and then extends through the carrier plate 11 to engage the free end of the long arm 18a of the more remote lever 17a. The two lever arms 18a, 18b are forked at their ends to accommodate the operating rod 25 between them and the lever arm 18a carries a pin 28 engaged by an eye in the end of the operating rod 25 so that a pull on the rod swings lever-arm 18a inwards and in such movement also moves the lever-arm 18b inwards and swings the short arms 19a, 19b outwards to press the shoes 12, 13 into contact with the drum 10.

A stop 29 is provided on the carrier-bracket 15 to be engaged by a nose 30 on the end of lever-arm 18a to limit the outward movement of the lever-arms 18a, 18b under the action of the pull-off 14.

Sufficient clearance is provided in the eye on the operating rod 25 and between the forked ends of lever-arm 18a, 18b so that angular displacement of the rod is possible.

The brake-shoes 12, 13 are of the ordinary T section with the friction lining on the outer side, and the stem of the T directed inwards, and each of the operating levers 17a, 17b is provided on its short arm 18a, 18b with a slot 31 to engage the end of the stem of the T. The expander mechanism is secured, as mentioned above, to the carrier-plate 11 so that the equivalent of a fixed cam is obtained, which gives equal shoe-travel and equal lining-wear, together with a straight line relationship of brake-factor against lining-friction-coefficient. In order to provide the desired braking effect, a servo motor may be used.

Alternatively the expander mechanism can be allowed to float on the carrier-plate 11, in which case a differential effect arises as between a leading and a trailing shoe. This is advantageous in some circumstances in that a greater braking effect can be obtained owing to the self-applying action of the leading shoe.

In either case an adjuster is required to take care of lining wear, and this can conveniently be of the known type which expands the shoe-abutment points.

The general advantages of this invention are simplicity of construction, ability to operate satisfactorily without lubricant, freedom from chocking with dirt, and greater mechanical efficiency especially if dirt gets access to the mechanism as is sometimes the case.

I claim:

1. In a brake having a brake drum, a pair of internal expanding brake shoes within the drum, a carrier plate for supporting the brake shoes, and pull-off spring means to urge the brake shoes from engagement with the brake drum; an expander mechanism comprising a bracket comprising a base portion adapted to be supported from the carrier plate and a pair of spaced apart limbs upstanding from said base portion and forming therebetween a channel extending substantially from the free end of one brake shoe to the free end of the other brake shoe, the edges of the limbs adjacent each brake shoe being formed with aligned part-circular recesses of small radius of curvature, a pair of bell-crank levers, one for each brake shoe, each bell-crank lever having a short arm, a long arm and a pair of laterally extending trunnion elements, each of such dimensions as to withstand the operating loads and each having a small radius of curvature bearing surface, each bell-crank lever being disposed with its short arm engaged with its as-

sociated brake shoe, with the bearing surfaces of its trunnion elements engaged in a pair of the aligned part-circular recesses, and with its long arm extending within the channel from one end thereof towards the other end, the inner ends of said bell crank levers being overlapped and in contact, the contacting surfaces being rounded to have substantially rolling contact upon one another incident to the rocking movements of said levers; and an operating member adapted to engage the inner end portion of the long arm of one of the bell crank levers to rock it and through the rounded surfaces rock the other bell crank lever by applying a load to said one bell crank lever in a direction such that the loads on the bell crank levers retain said bearing surfaces of the laterally extending trunnion elements in engagement with the part-circular recesses.

2. In a brake of the class comprising a brake drum, a pair of internally-arranged brake shoes to co-operate with the brake drum, a carrier plate for supporting the brake shoes, pull-off spring means to urge the brake shoes out from engagement with the brake drum, and an expander mechanism for moving the brake shoes into engagement with the brake drum; a construction of expander mechanism comprising a pair of bell-crank levers, one for each brake shoe; each bell-crank lever having a long arm, a short arm, and a pair of laterally extending parts at the junction of the long and short arms; each laterally extending part forming a trunnion for the bell-crank lever, having such dimensions as to withstand the operating loads and having an arcuate edge of small radius of curvature; a channel-section bracket having a pair of limbs upstanding from a base portion and adapted to be supported by the carrier plate with its channel extending from adjacent the end of one brake shoe to adjacent the end of the other brake shoe, the limbs being formed in each of their end edges with small radius part-circular recesses, the recesses in the adjacent ends of the limbs being aligned; the bell-crank levers being disposed in the channel-section bracket with their short arms engaged with the respective brake shoes, with their long arms extending from one end of the channel towards the other end with the arcuate edges of their laterally extending parts engaged with a pair of said aligned recesses; said long arms overlapping and being engaged through rounded surfaces to provide substantially rolling contact therebetween; and an operating member connected with one bell-crank lever to rock it and thereby through said rounded surfaces to rock the other bell-crank lever, by applying a load to said one bell-crank lever in a direction such that the loads on the bell-crank levers retain said arcuate edges in the recesses.

3. An expander mechanism as claimed in claim 2, wherein said laterally extending parts are each of wedge-form having their narrower end shaped to provide the arcuate edges of small-radius of curvature.

4. For use in expanding spring-retracted brake shoes against a brake drum, an expander mechanism comprising a pair of spaced walls lying in planes substantially normal to the plane of movement of the brake shoes and cross-wise between the free ends of the brake shoes with end edges of said walls adjacent the ends of the brake shoes having rounded bearing recesses open at their outer sides, bell-crank levers having long and short arms disposed between said

walls and between the free ends of the brake shoes, with the short arms engaging with said brake shoes, trunnions projecting laterally from said bell crank levers in opposite directions and fitted to rock in said recesses, said trunnions having rounded inner portions conforming generally to the curvature of said recesses to enable the levers to rock on said trunnions in said recesses, said trunnions being rounded only at their inner end portions and having massive outer non-circular portions to reinforce and strengthen the inner rounded bearing portions, the long arms of said levers lying longitudinally of one another with the inner end portions overlapped, said levers having mutually rounded bearing contacting surfaces at their overlapped portions, and an operating member connected with one inner end portion of one lever for moving the same toward the overlapped portion of the other lever incident to expanding the brake shoes to cause the overlapped rounded surfaces to roll upon one another and the rounded inner trunnion surfaces to rock in said recesses and to cause the rounded inner trunnion surfaces to seek the recesses incident to the brake loads transmitted by said operating member to said levers.

5. An expander mechanism as claimed in claim 4 further comprising pins extending laterally beyond said trunnions and detents on the walls engaged by said pins to further hold the inner rounded surfaces of the trunnions in said recesses.
